FLUID ACTUATED PULLER

Augustus J. D'Antoni, Sr., 6646 Hooper Road,
Baton Rouge, La. 70811

Filed June 20, 1974, Ser. No. 481,150

Term of patent 14 years

Int. Cl. D8—05

U.S. Cl. D8—51

FIG. 1.

FIG. 2.

FIG. 3.

FIG. 1 is a perspective view of a fluid actuated puller showing my new design;

FIG. 2 is a top plan view of the device of FIG. 1; and
FIG. 3 is a side view of the device of FIG. 1.

I claim:

The ornamental design for a fluid actuated puller, substantially as shown.
